UNITED STATES PATENT OFFICE.

CHARLES E. ONGLEY, OF NEW YORK, N. Y., ASSIGNOR TO GEORGE J. SCHOEFFEL, OF SAME PLACE.

ELECTRICALLY-CONTROLLED STEERING DEVICE.

SPECIFICATION forming part of Letters Patent No. 561,272, dated June 2, 1896.

Application filed December 8, 1893. Serial No. 498,149. (No model.)

To all whom it may concern:

Be it known that I, CHARLES E. ONGLEY, a citizen of the United States, residing at New York city, in the county and State of New York, have invented a certain new and useful Improvement in Steering Devices Controlled Electrically, of which the following is a specification.

My invention relates to the steering apparatus of a ship, and particularly to a motor for the operation of the rudder and means to control the same electrically, together with means to arrest the movement of the rudder and hold the same in one position when the motor is inoperative, and means controlled electrically to shift the operative connection with the rudder, so that it may be operated either by hand or otherwise at will.

I have illustrated my device in the accompanying drawings, in which like letters refer to like parts throughout.

Figure 1 is a view in elevation showing the valve partially in section and the circuit connections. Fig. 2 is a side view of the same in elevation. Fig. 3 is a sectional view of the motor. Fig. 4 is a top view of the same, showing its connection with the rudder. Fig. 5 is a view showing the supply and exhaust valves, together with the magnets, the same being partially in section.

In operating my device I prefer to use steam-pressure to operate the motor, but I may employ hydraulic or other pressure. The steering-wheel and electric switches and dial, hereinafter to be described, are intended to be in the pilot-house, conveniently arranged to be operated by the hand of the pilot, while the motor and all of the operative parts, herein-after to be described, are located in the stern 40 of the ship in convenient proximity to the rudder.

The motor that I employ preferably is shown in section in Fig. 3. It consists of three cylinders A, a', and a''. These cylinders are provided with ports a³, a⁴, a⁵, a⁶, a⁷, and a⁸. The ports a³ and a⁷ are connected together by the pipe a¹⁵, having a valve therein. The ports a⁴ and a⁸ are connected by the pipe a¹⁶, also having a valve therein. The cylinder A is provided with a piston-rod a⁹ with a centrally-located head a¹⁰. The cylinders a' and a'' are

provided with the piston-rod a¹², having two heads a¹³ and a¹⁴. The space within the cylinders a' and a'' and between the heads a¹³ and a¹⁴ and also the cylinder A is filled with water or equivalent liquid, (indicated at y y.)

B is a frame sustaining the above-described cylinders and having journaled between its arms the shaft b'. Secured to this shaft is the pinion b², and the sleeve or clutch-wheel b⁴ is also secured to revolve with said shaft, but free to have a vertical movement upon the same. It is provided with teeth on both sides. The pulley b³ and the pinion b⁵ are loosely mounted upon the shaft b' and provided with teeth to mesh with the teeth of the sleeve or clutch-wheel b⁴.

b⁶ is a lever pivoted at b⁸ and provided at one end with a fork, between which the sleeve or clutch-wheel b⁴ is pivoted at b⁷ and b⁷ and provided at the other end with the teeth b⁹.

b¹⁰ is a rack secured to the ends of the piston-rod a⁹ and provided with the teeth b¹¹, engaging the pinion b⁵.

C represents the rudder-post, and c' is a quadrant engaging the pinion b².

D is a shaft journaled in the brackets d' and d'' and provided with the hand-wheel d³ and the screw d⁴, which is secured thereto and arranged to engage the teeth d⁹ of lever d⁶.

d⁵ is a cylinder suitably mounted, having a piston-rod d⁶, which is provided with teeth in the form of a rack to engage the pinion d⁷, which is secured to the shaft D. The cylinder d⁵ is provided with valves d⁸ and d⁹.

d¹⁰ and d¹¹ are electromagnets in circuit, having their armatures d¹² and d¹² secured to the valves d⁸ and d⁹.

d¹³ is an electric switch-handle, and d¹⁴ and d¹⁵ are contact-points for said handle.

x³ is a battery of the source of electrical supply located in the circuits to the magnets d¹⁰ and d¹¹, and the switch-lever d¹³ controls the circuit to said magnets.

E is a steering-wheel controlling the pulley e' and having a rope or chain passing around the same and over suitable pulleys to the pulley b³.

F is a supply-pipe, and f' is an exhaust-pipe. The valve to which this supply and exhaust lead is shown in Fig. 5. The pressure lies in the space f² and against the valves f⁹ and f³.

f^8 is a plunger provided at one end with the valve-head f^9 and at the other with a head arranged to oscillate in a cylinder, the spring f^{10} holding the valve f^9 in position.

5 f^4 is a valve-stem controlling the valve f^3 , and f^7 is a spring holding the same in the closed position.

f^5 is an electromagnet in circuit, and f^6 is an armature for said magnet, secured to the 10 valve-stem f^4 .

f^{11} are a series of ports or perforations.

f^{12} is a plunger provided with two heads f^{13} and f^{14} . I have described half of this valve. The other side being the duplicate thereof it 15 will be unnecessary to enumerate its parts.

f^{15} is a pipe leading from said valve, thus described, into the cylinder a^2 , and f^{16} is a pipe leading into the cylinder a' . The electromagnets f^5 and f^{20} are in circuit with the 20 battery or other source of electrical supply x' , and said circuit is controlled to either of said magnets by the electric switch f^{17} , having contact-points f^{18} and f^{19} .

G is a cylinder having a piston-rod g' in the 25 form of a rack. g^2 is a stop-cock, and g^3 is a pinion controlling said stop-cock engaging the rack g' . g^4 and g^5 are valves for said cylinder G .

g^6 and g^7 are electromagnets in circuit, having 30 armatures g^8 and g^9 connected with the valves g^4 and g^5 .

g^{10} is an electric switch having the contact-points g^{11} and g^{12} .

x^2 is a battery or other source of electrical 35 supply in the circuit to the magnets g^6 and g^7 , said circuit being controlled by the electric switch g^{10} .

H is a dial carrying a pulley, over which passes a cord, the movement of which is controlled by the sprocket-wheel h' , which is 40 mounted on the shaft b' .

I will now describe the operation of my device and relate first the operation of the means by which I shift the operative connections between the rudder and the steering devices, so 45 that the same may be used either with my apparatus or otherwise. I can either do this by means controlled electrically or by hand.

Should I desire to perform the operation 50 by hand, I do so by moving the hand-wheel d^3 . This operates to throw the clutch wheel or sleeve b^4 into or out of engagement with the pulley b^3 or the pinion b^5 . When the same is thrown into engagement with the 55 pulley b^3 , I can control the rudder with the steering-wheel E without interfering with any of the other apparatus. Should I desire to control this operation electrically, I do so by means of the switch d^{13} —that is to say, by 60 bringing the same into contact with either of the contact-points d^{14} or d^{15} —thus energizing either one or the other of the electromagnets d^{10} or d^{11} , and operating the valves d^8 or d^9 to admit pressure into the cylinder d^5 either to 65 throw the piston-rod d^6 backward or forward, as the case may be, to perform the operation last described by the hand movement. These

valve-controlling devices being so well known in the art I deem it unnecessary to describe them further. In the drawings the clutch 70 wheel or sleeve b^4 is shown in engagement with the pulley b^3 —that is, in position to be operated by hand. When the same is shifted to be in engagement with the pinion b^5 , the rudder is thrown into the control of the motor, the operation of which will now be described. In the first place, should I desire to operate the same to admit or cut off steam, I move the switch g^{10} to either of the contact-points g^{11} or g^{12} , thus making the circuit to either the 80 magnet g^6 or g^7 , as the case may be, and thus operating the valves of the cylinder G , admitting steam to operate the piston-rod g' to move the pinion g^3 to open or close the valve or stop-cock g^2 . The pressure being admitted, as last described, the steam lies in the space in said valve f^2 and f^3 against the valve-heads f^9 and f^{13} . Should I desire to admit pressure to the cylinders a' or a^2 , I operate the electric switch f^{17} , bringing the same 85 either onto the contact-point f^{18} or f^{19} , thus energizing, according to such movement, either the magnet f^5 or f^{20} . Suppose that I energize the magnet f^5 . This will attract the armature f^6 and operate to open the valve f^3 , 90 admitting pressure through the same to bear upon the head of the plunger f^8 against the tension of the spring f^{10} and open the valve f^9 and admit the pressure through the ports f^{11} and operate to drive the plunger f^{12} into 95 a position in which the head f^{13} will close the port z and prevent the escape of the pressure through the exhaust f' . The pressure will then pass into the pipe f^{15} and thence into the cylinder a^2 . It will be noted that with 100 the movement of the plunger f^{12} the head f^{14} is moved away from the position in which it closes the port z , thus permitting an exhaust of any steam lying in the pipe f^{16} through the exhaust f' . The reverse movement of 105 course permits an exhaust from the pipe f^{15} . Referring now to Fig. 3, it will be seen that I employ water or equivalent liquid to fill the cylinder A and the cylinders a' and a^2 between the heads a^{14} and a^{15} , and indicate the 110 same by y . With the introduction of the steam through the pipe f^{15} and port a^5 into the cylinder a^2 the head a^{14} will be moved by 115 said pressure, thus forcing the liquid from before said head into the cylinder A by the pipe a^{15} and thus moving the head a^{10} and in like manner forcing the water from before 120 said head through the pipe a^{16} into the cylinder a' , and any steam lying in the cylinder a' will be driven through the pipe f^{16} and port z' 125 out through the exhaust f' . I interpose this hydraulic resistance or tension into the motor for the purpose of establishing a check or lock on the movement of the rudder to hold it in a position into which it may have been 130 moved by the operative power, the tension or resistance being the amount of power necessary to displace the water or other liquid by forcing it through the pipes connecting the

cylinders. This tension may be increased or diminished by the operation of the valves in the pipes connecting the cylinders. This will be manifest, as the smaller the channel the greater the resistance. I have shown this resistance interposed in the motor. It will be manifest, however, that I may employ the same in any convenient manner and with any form of motor, or the resistance may be applied directly to the rudder. With the movement of the head a^{10} , as last described, the piston - rod a^9 will move the rack b^{10} , and through the pinion b^5 and clutch-wheel b^4 the shaft b' , the pinion b^3 , the quadrant c' , and the rudder-post C. The reverse movement hereof is, of course, identical with that last described, being controlled by the switch f^{17} to admit pressure into either the cylinder a' or a^2 .

20 The dial or index H operates, as heretofore described, with the shaft b' through the sprocket-wheel h' to indicate the position of the rudder.

What I claim is—

25 1. In a steering device, the combination of a hydraulic cylinder, a piston movable in said cylinder and connected with and operating the rudder, two steam-cylinders mounted adjacent to said hydraulic cylinder, pistons in said steam-cylinders connected together, a supply-pipe connecting one end of each steam-cylinder with one of the ends of the hydraulic cylinder and a liquid filling said hydraulic cylinder, and the spaces behind or in front 30 of the pistons in the respective steam-cylinders to which said supply-pipes are connected, substantially as set forth.

40 2. In a steering device, the combination of a hydraulic cylinder, a piston movable in said cylinder and connected with and operating the rudder, two steam-cylinders mounted adjacent to said hydraulic cylinder, pistons in said steam-cylinders connected together, a contracted supply-pipe connecting one end 45 of each steam-cylinder with one of the ends of the hydraulic cylinder and a liquid filling said hydraulic cylinder, and the spaces behind or in front of the pistons in the respective steam-cylinders to which said contracted supply-pipes are connected, substantially as set forth.

45 3. In a steering device, the combination of a hydraulic cylinder, a piston movable in said cylinder and connected with and operating the rudder, two steam-cylinders mounted adjacent to said hydraulic cylinder, pistons in said steam-cylinders connected together, a supply-pipe connecting one end of each steam-cylinder with one of the ends of the hydraulic 50 cylinder, a liquid filling said hydraulic cylinder, and the spaces behind or in front of the pistons in the respective steam-cylinders to which said supply-pipes are connected, and

valves in said supply-pipes for reducing the passage of the liquid through the same, substantially as set forth. 65

4. In a steering device, the combination of a hydraulic cylinder A, a piston therein connected with and operating the rudder, two steam-cylinders a' , a^2 , mounted adjacent to 70 said hydraulic cylinder, pistons in said steam-cylinders connected together, supply-pipes connecting the forward ends of the steam-cylinders with both ends of said hydraulic cylinder, the spaces in front of the piston of 75 each steam-cylinder and the hydraulic cylinder being filled with a liquid, steam-pipes connecting with the steam-cylinders behind the pistons therein, and means for controlling the entrance of steam to said steam-cylinders, 80 substantially as set forth.

5. In a steering device, the combination of a hydraulic cylinder A, a piston therein connected with and operating the rudder, two steam-cylinders a' , a^2 , mounted adjacent to 85 said hydraulic cylinder, pistons in said steam-cylinders connected together, supply-pipes connecting the forward ends of the steam-cylinders with both ends of said hydraulic cylinder, the spaces in front of the pistons of 90 the steam-cylinders and the hydraulic cylinder being filled with a liquid, steam-pipes connecting with the steam-cylinders behind the pistons therein, and means for electrically controlling the entrance of steam to said cylinders, 95 substantially as set forth.

6. In a steering device, the combination with means for operating the rudder mechanically and means for operating said rudder through an engine controlled electrically, of 100 clutch mechanism so constituted and arranged, relatively to said rudder, as to permit either one of said mechanisms for operating the rudder to be employed, a motor for operating said clutch mechanism and means 105 for controlling said motor electrically, substantially as described.

7. In an electric steering-gear, the combination of the rudder, a main shaft for controlling the same, a clutch on said main shaft, 110 a motor adapted to be connected with said main shaft through said clutch, means for controlling said motor electrically, a hand steering device adapted also to be connected to said main shaft by said clutch, and means 115 controlled electrically from the bow of the vessel for throwing said clutch into engagement with said motor, or with the said hand steering-gear, substantially as set forth.

This specification signed and witnessed this 120
22d day of November, 1893.

CHARLES E. ONGLEY.
